EYELASH CURLER

Percy A. Brown, Quantico, Va.

Application January 10, 1947, Serial No. 721,296

1 Claim. (Cl. 132—32)

1

Generically this invention relates to hair curling devices, but it is more specifically directed to new and useful improvements in an eyelash curler.

One of the principal objects of this invention is the provision of a unique and compact structural arrangement embodying a casing including a stationary member, and a vertically movable member surmounting said stationary member and telescopically arranged in said casing for movement downwardly into operative engagement with said stationary member.

Another important object of this invention is the provision of simplified and novel means including spring controlled push-button means for operating said movable member.

A still further important object of the invention is the provision of a compact casing composed of complemental demountable sections, the upper end of said demountable sections adapted to support the stationary eyelash member, said casing adapted to house the stem portion of the movable eyelash engageable jaw member overlying its complemental stationary jaw member and operating mechanism therefor, and manually operable means for effecting reciprocal movement of said stem.

With these and other objects in view, which will become apparent as the description proceeds, the invention resides in the construction, combination, and arrangement of parts, hereinafter more fully described and claimed, and illustrated in the accompanying drawings, in which like characters of reference indicate like parts throughout the several figures, of which:

Fig. 1 is a side elevation of my improved eyelash curler showing movable parts in dotted lines.

Fig. 2 is a front elevation looking in the direction of the arrow A shown in Fig. 1.

Fig. 3 is a rear elevation looking in the direction of the arrow B shown in Fig. 1.

Fig. 4 is a central vertical longitudinal section taken on the line 4—4 of Fig. 2 with parts in section and showing the eyelash engaging members in open position.

Fig. 5 is a similar view to Fig. 4 showing the eyelash members in closed or eyelash curling position.

Fig. 6 is a horizontal section taken on the line 6—6 of Fig. 4.

Fig. 7 is a horizontal section taken on the line 7—7 of Fig. 4.

Fig. 8 is a horizontal section taken on the line 8—8 of Fig. 4.

Fig. 9 is a horizontal section taken on the line 9—9 of Fig. 4.

2

Fig. 10 is a horizontal section taken on the line 10—10 of Fig. 4.

Fig. 11 is an enlarged fragmentary sectional view through the movable and stationary jaw elements showing a modified construction of a stationary jaw element.

Fig. 12 shows a sectional view of a further modification with a movable jaw in open position.

Fig. 13 is a similar view to Fig. 12 with the movable jaw in closed or operative engagement with the lower jaw element.

Fig. 14 is a detail top plan view of the lower jaw element with parts broken away and in section.

Fig. 15 is a view similar to Fig. 14 of another modified form of one of the jaw members showing an adjusting means mounted thereon.

The devices of this general character with which I am familiar have proven deficient and unsatisfactory for various reasons, some of which are; manually operable means of cumbersome construction making the device unwieldy to handle, difficult to carry in a small container or in the pocket, and, further, by reason of exteriorly mounted connections between the jaws and the operating means, manually operable means usually mounted at the end of the device opposite to the jaw element tending to render it difficult to operatively position the device. It was therefore to overcome these and other disadvantages, by providing a device wherein the body portion of the device constitutes a support for the jaws and at the same time forms a casing to house most of the operating parts of the device, and, at the same time, permitting ready demounting of the device and replacement of parts, the casing portions being formed with an interior guide channel for the reciprocating stem of the upper jaw and with an enlarged hollow space for housing the simple operating coating mechanism between the stem and push-button, the movable jaw being spring-controlled, and when assembled said parts constituting a compact, easily handled instrument, that I designed the device forming the subject matter of this invention.

In the illustrated embodiment characterizing this invention there is shown an eyelash curling device C comprising a body or casing portion D, said portion D including a pair of separable complemental sections 1 and 2. The casing D is formed, spaced from its upper end, with a solid outwardly projecting portion 3, and intermediate said portion 3 and the free end of the device on the opposite side thereof, said casing D is formed

with a hollow dome-like projection 4, said casing curving slightly upwardly at its free end as at 5, and substantially curving upwardly at the opposite end from 6 to 7.

The upper surface of the casing D is convexed as shown in Figs. 1, 2 and 3, and mounted on the end of the casing is a stationary arcuate lower jaw element 8, in the present instance, formed with a channel 9 in which is frictionally or otherwise mounted a resilient upper jaw engaging member 10, said member 8 being secured at spaced points to the respective end walls of sections 1 and 2 by screws 11 or in any suitable manner.

Each of said sections 1 and 2 is formed with a complementary longitudinal bore or groove 12 intersecting the hollow space 13 within dome 4, and extending substantially throughout the length of said sections and terminating in opening 14 when the sections are assembled. Section 2 is formed on its inner face with openings 15 adapted, when said sections are assembled, to frictionally receive the complementary dowels 16 formed on the meeting face of section 1, and which maintains the sections united to form the casing D as will be well understood.

A complementary movable blade-like jaw element 17 is riveted, welded, or otherwise suitably secured to the free ends of yoke portion 18, the latter being formed with an elongated stem portion 19 adapted for telescopic reciprocal engagement in bore 12, and, in the present instance, is formed with a countersunk opening 20 on one surface terminating at its upper edge in an arcuate flange 21; said opening is adapted to receive the free end of the shorter arm 22 of a bell-crank element 23 pivotally mounted on pin 24, the free end of the other arm 25 of said bell-crank being formed with a pivot head 26 adapted to engage the enlarged inner-head 27 suitably formed on push-button 28, the shank or stem 29 of which extends through opening 30 in dome portion 4. Intermediate the end of stem portion 19 and the end wall of bore 12 is positioned a compression or coil spring 31 for a purpose directly more fully appearing.

It is understood that the parts of the instant invention, while primarily shown as constructed of metal, may be constructed of plastic or other suitable material. Fig. 11 shows a modification wherein the lower jaw element 32, corresponding to jaw 8, is constructed of plastic and formed with a channel 33 in which is positioned the insert 34 formed with a V-shaped recess 35 and constructed of semi-resilient material, such as plastic, rubber, or the like, said recess adapted to receive the blade-like movable jaw 36 corresponding to jaw 17, so that when the eyelash is positioned over said recess, downward movement of the jaw 36 within recess 35 will effect the curling operation similar to the action of jaw 17 when moved into eyelash engaging position with respect to the resilient jaw engaging member 10.

Fig. 12 shows a further modification wherein the lower jaw element 37, corresponding to jaw 8, is shown constructed of metal and formed with a recess or channel 38, but may be constructed of plastic or other suitable material, and in this form, instead of insert 10 or 34, member 37 is inserted in channel 38 and enveloped by a resilient or rubber-like tube 39, and the movable jaw 40, corresponding to jaw 36, is shown in retracted or open position. Fig. 13 shows jaw 40 in lower jaw engaging eyelash curl-

ing position, wherein the tube member 39 is depressed within recess 41 formed in said tube member and which corresponds to channel 35 as above described, said tube assuming its normal position as shown in Fig. 12 upon return of jaw 40 to open position.

Fig. 14 shows a further modification wherein the lower jaw 42 has a metal strip 43 pre-shaped to any desired arc and secured to the outer face of said member by rivets 44 extending through member 42 and adapted to shape and hold said member in such adjusted position.

In Fig. 15 another modification is shown wherein a lower jaw 45, corresponding to jaw 8 for instance, has a pair of spaced brackets 46 secured to the outer surface of said jaw by screws or rivets 47, and having spaced outwardly projecting ears 49 formed with registering threaded openings one of which is threaded, adapted to receive the threaded shank 50 of thumb-bolt 51 so as to vary the curvature or arc of jaw member 45 by tightening or loosening said bolt 51 to adjust said jaw in conformity with the contours of different shaped eyelashes. While the adjusting means just described is, for instance, shown attached to a lower jaw 45, it is to be understood that a similar adjusting means is also mounted on and secured to its complementary upper jaw so as to effect a corresponding adjustment thereof.

To effect the eyelash curling operation it is only necessary to position the device C so that the eyelash will extend between the jaws 8 and 17 for instance, and operation of the push-button 28 depresses the pivot-head 26 causing arm 22 of bell-crank 23 to retract stem 19 against the action of coil spring 31 and bring upper jaw 17 into binding engagement with the resilient element 10 of lower jaw 8 so as to embed said jaw therein as shown in Fig. 5, to effect the curling operation, and upon removal of pressure upon push-button 28, spring 31 will return jaw 17 to its initial normally open position as will be clear without further discussion.

From the above it will be apparent that I have designed a device simple in construction, compact in form, easily manipulated, comprising few parts, manufacturable at a minimum of production cost, and efficient for the purposes intended.

Although in practice it has been found that the form of the invention illustrated in the accompanying drawings and referred to in the above description as the preferred embodiment is the most efficient and practical, yet realizing that conditions concurrent with the adoption of the invention will necessarily vary, it is desired to emphasize that various minor changes in details of construction, proportion and arrangement of parts, may be resorted to within the scope of the appended claims without departing from or sacrificing any of the principles of this invention.

Having thus described the invention, what I desire protected by Letters Patent is as set forth in the following claim:

An eyelash curler comprising a sectional casing, the respective sections being formed with portions angularly extending beyond the end of the casing proper and forming seats, an arcuate lower jaw fixedly secured to said seats, said sections being formed to provide, when secured in meeting engagement, a dome-like projection forming a chamber on one side of the casing, a solid outwardly projecting portion intermediate said dome portion and lower jaw on the opposite side of the casing, and a guide channel substantially coax-

tensive with the length of the casing and intersecting said chamber, a complementary eyelash engaging upper jaw element including a spring controlled stem member movably arranged in said guide channel, said upper and lower jaws being in vertical alignment, a bell-crank element pivotally mounted in said dome with one end engaging said stem, a single depressible operating means coacting with the free end of said bell-crank and extending to the exterior of said dome projection operable to produce movement of the upper jaw member to effect eyelash curling engagement of said upper jaw with said lower jaw against said spring control action, the construction and arrangement of said casing and dome and solid projections being such as to provide a comfortable finger engaging formation and positioning the single operating means for actuation

thereof by the thumb during the curling operation.
